UNITED STATES PATENT OFFICE

ISAAC M. PEASE, OF CINCINNATI, OHIO, ASSIGNOR TO THE OHIO TRUSS COMPANY, A CORPORATION OF OHIO

ABDOMINAL SUPPORT

Application filed April 5, 1928. Serial No. 267,733.

My invention relates to abdominal supporting belts. In belts of the type mentioned, under the varying conditions of uses, it becomes desirable at times that the belt should be provided with steel ribs, or bones, to stiffen the same vertically, whereas at other times such steel ribs or bones are not desirable, by reason of the fact that they may produce irritation and thus interfere with the comfort and welfare of the wearer.

The principal object of the present invention is to provide means whereby the steel ribs or bones may be readily inserted or removed.

Further objects of the invention will appear from the following detail description thereof.

In the drawings:

Figure 1 is an elevation of an abdominal supporting belt constructed in accordance with this invention.

Figure 2 is an elevation of a detail.

Figures 3 and 4 are sectional views of the invention, and Figure 5 is an elevation similar to Figure 2 showing the rib in place for use.

The numeral 1 indicates an abdominal supporting belt constructed of fabric or other suitable material. The belt 1 is provided with a tape or tapes 2 which are stitched to the belt in substantially vertical relation thereto and adapted to form casings for the steel or bone ribs 3. The belt, under the tape 2 is provided with a pocket 4 formed by a small piece of leather 5 stitched to the belt, one end of the tape 2 being open as shown at 6 over said pocket, to provide for the insertion of the ribs 3 as shown particularly in Figure 4 of the drawings. When the rib has been inserted, the end passes under the edge 7 of the pocket, and may be inserted therein, as shown in Figure 3, in which position the rib is held fixedly in the channel formed by the casing 2. In order to remove the rib, the end thereof is removed from the pocket and drawn outwardly through the opening 6 which will be readily understood.

From the foregoing description the nature and construction of the present invention will be apparent to those skilled in the art to which the same appertains. As will be seen,

when desired the belt may be provided with steel or bone ribs to rigidify or stiffen the same vertically. When, however, the condition or comfort of the wearer so indicates, the rib may be removed from the pocket as indicated and withdrawn from the casing formed by the tape 2.

Having thus fully described my invention, what I claim as new and desire to secure by Letters Patent is:

In combination with a belt of the character described, a stiffening rib for said belt, a tape stitched to said belt so as to form a channel thereon for said rib substantially coextensive therewith and having one of its ends open, a piece of material secured to said belt and extending into the open end of said channel and having its side edges stitched therein to form a pocket, said pocket being adapted to receive the end of the rib to retain same in said channel.

ISAAC M. PEASE.
